UNITED STATES PATENT OFFICE

106,457

DESIGN FOR A COMBINED TELEPHONE DESK STAND AND HANDSET

Rudolph Frank Stehlik, Antwerp, Belgium, assignor to Associated Telephone & Telegraph Company, Chicago, Ill., a corporation of Delaware

Application March 11, 1937, Serial No. 68,112
In Belgium November 13, 1936

Term of patent 14 years

To all whom it may concern:

Be it known that I, Rudolph Frank Stehlik, a citizen of the United States of America, and resident of Antwerp, Belgium, have invented a certain new, original, and ornamental Design for a Combined Telephone Desk Stand and Handset, of which the following is a specification, reference being had to the accompanying drawing, forming part thereof.

Fig. 1 represents a front perspective view and Fig. 2 represents a rear perspective view of the combined telephone desk stand and handset, showing my new design.

I claim:

The ornamental design for a combined telephone desk stand and handset as shown.

RUDOLPH FRANK STEHLIK.
